UNITED STATES PATENT OFFICE.

WILLIAM J. NEIDIG, OF MADISON, WISCONSIN, ASSIGNOR TO NEIDIG TYPEWRITER CO., OF CHICAGO, ILLINOIS, A CORPORATION OF ILLINOIS.

TYPE-WRITING MACHINE.

1,112,408.

Specification of Letters Patent. Patented Sept. 29, 1914.

Application filed December 4, 1912. Serial No. 734,869.

To all whom it may concern:

Be it known that I, WILLIAM J. NEIDIG, a citizen of the United States, residing at Madison, in the county of Dane, State of Wisconsin, have invented a certain new and useful Improvement in Type-Writing Machines, of which the following is a specification, reference being had therein to the accompanying drawings.

10 Certain principles and features of my invention as described herein are included within the generic invention which is described and claimed in Letters Patent No. 1,053,919, granted Feb. 18, 1913, upon my 15 co-pending application filed April 20, 1908, Serial No. 428,212.

One of the objects of my general invention is to indicate to the operator of a type-writing machine the decreasing distance 20 from the current printing point to the bottom end of the sheet, and this without preliminary care on his part, automatically. Other objects are to supply him with improved indicating means of various types 25 for indicating the arrival of the sheet into a predetermined line position.

The present branch or division of the invention has as features certain novel constructions and combinations adapted to 30 render the invention more useful in practice, including a novel form of reciprocating paper-feeler; a novel use of a cam and cam-follower in paper-controlled devices; an index-carrier of novel construction; a novel 35 combination of elements making use of a feeler-retracting spring; a special form of light-acting bell-signal and machine-lock-signal mechanism adapted for use with the actuating means herein shown; and other 40 novel constructions and combinations, as will be hereinafter explained.

In the drawings—Figure 1 is a view in end elevation of portions of a type-writing machine showing my device as applied 45 thereto. Fig. 2 is a top or plan view of portions of the same. Fig. 3 is an end view of portions of Fig. 1, with certain structural details indicated. Fig. 4 is a detail view. Figs. 5 and 6 represent alternative forms of the detail shown in Fig. 4. Fig. 7 is a front view of the parts shown in Fig. 3. Fig. 8 is a detail shown in cross-section, on the line 8—8, Fig. 3. Fig. 9 is a representation in cross-section of the structure

55 parts on the platen-arbor. Fig. 10 is an end elevation of a modification in the form and mounting of certain of the controlling parts. Fig. 11 is a front view of the same. Fig. 12 is an end elevation of a modification. 60 Fig. 13 is a front view of the same. Fig. 14 is an end elevation of another modification, partly in section. Fig. 15 is a front view of the same, with the platen frame indicated. Fig. 16 is an end elevation of a 65 modification, partly in section. Figs. 17 and 18 are end elevations of another modification, partly in section. Fig. 19 is a representation in cross-section of the structure of parts of the same, on the line 19—19, 70 Fig. 18.

With reference to the drawings,—Carriage frame 12, movable laterally in usual manner upon the main frame 41 of the typewriting machine, has mounted upon it 75 shifting platen frame 47, supplied with the usual supporting and controlling mechanism, journaled in the ends of which is platen arbor 13 bearing platen head 39 of the sheet-advancing platen-roll 10, operated 80 by line spacing mechanism as in practice and not shown herein. The usual paper table for the support of the entering sheet is indicated at 8, the same being carried in usual manner upon the platen frame 47. 85 Typewriter structure such as is referred to is well-known and need not be more closely described herein. In applying an embodiment of the present invention to this structure (Fig. 9) against the end of the platen 90 10 is placed a friction washer 11, preferably made of leather or cardboard. The washer is not essential. Against the washer is placed operative member 6, 95 through which the several types of indicating means desired to be employed are called into operation. As here shown, this member is journaled upon platen-head 39 and is constructed as an annular shell having an internal shoulder. Against said shoulder 100 bears a thrust-ring 84 of sheet-metal a flange of which receives axially-directed pressure from a diaphragm spring 7. Member 6 bears a projection 18, used also as a key-pin to keep spring 7 from shifting angularly 105 thereon. Thrust-ring 84 is discontinuous, i. e., a split ring, the projection passing between the two ends thereof. Diaphragm

spring 7 is preferably supplied with radial slits 31 (Fig. 4) in order to relieve the transverse strains and render the spring more flexible, though a spring without openings, like that shown in Fig. 5, at 7^a may be used, or one with other than radial openings, like that shown in Fig. 6 at 7^b. Spring 7 may if desired be protected from the wear of thrust-collar 33, attached upon 10 platen-head 39 by means of set-screw 9, by a thrust-washer 35, conveniently attached to said spring by rivets 61. Disk 25, conveniently attached by means of the same rivets, is provided with threaded seats or 15 holes 67, into one of which may be screwed a pin 68, through suitable openings in the spring.

Preferrably by means of bolt-clamps 46 and spring-clamp 46' platen-frame 47 has 20 attached against the flat inner side thereof a frame-plate 2 (Fig. 3), which is so shaped as to receive additional support from the cross-brace of the said frame. The purpose of the plate is to supply supporting structure for my mechanism without altering the existing structure of the machine; but it could of course be changed in form and manner of attaching, or omitted altogether, 25 as shown in some of my other figures. Plate 30 2 bears an inwardly projecting pin 20 (Fig. 8), which has independently journaled upon it end to end the bushings or hubs 21 and 21^a bearing respectively arm 32 and cam-stop 15. Stop 15 acts both as a stop and as a 35 lever—it normally lies in the path of pin 14, upon which it acts as a stop—but it is in turn acted upon by said pin and acts upon arm 32 and paper-feeler 28 thereon as a lever. Weight 111 tends to restore said stop 40 into the path of said pin 14. The stop is preferably constructed cam-shaped and having a cam surface 30, the purpose of the cam form being first, to give the stop as rapid action as may be desired under the actuation 45 of pin 14, second, to increase its angle of engagement with said pin and therefore its range of movement under the actuation thereof, and third, to lessen the pressure of paper-feeler 28 upon the sheet under the 50 actuation of pin 14; and it has other advantages. Said stop is therefore a cam, and pin 14 is a cam follower. The position of axle 20 within the arc described by pin 14 results in advantages in operation, the leverage being 55 more readily made to favor the sheet and the engaging angle of pin 14 and stop 15 being increased. A spring 66 attached to spring-post or pin 64 on plate 2 restores arm 32 to initial or normal position as shown 60 in Fig. 3. Arm 32 is supplied also with lugs 63 to coöperate with projection 62 on weight 111, forming a one-way joint or knuckle-joint, the purpose of the provision being to supply a backing-up means for pin 14 past 65 stop 15. Arm 32 bears the fixedly attached transversely-extending paper-feeler 28, which in the form shown in Figs. 1, 3, 7, 12, 13, maintains a position substantially parallel with the platen axis. Said paper-feeler has a path through the slot or opening 4 in the paper-supporting structure 8^a, preferably clamped upon rod 18 by means of bolt 19. I prefer to use a simple form of paper-feeler like the straight pin shown, having a path through a slot shaped to correspond. 70 Such a paper-feeler presents a minimum obstruction to the backing-up bottom edge of the sheet, instantly frees itself of it, can be made to reach as far past the printing margin α as is desirable, is strong, is simple of manufacture, has small inertia, can be operated in a cramped space, and by reason of its normal position against the platen is protected from injury by the platen.

The operation of this portion of the mechanism is as follows: A sheet of paper is inserted in usual manner and fed forward through the instrumentality of the platen. As the platen turns, member 6, frictionally connected therewith, also turns, together with projection 14 carried thereon. Eventually projection 14 meets cam surface 30 upon cam-stop 15 and rocks the cam-stop upon its axis 20. This action is communicated through projection 62 to arm 32 until 90 paper-feeler 28 meets sheet 45, as shown in Fig. 1. As paper-feeler 28 cannot pass through slot 4 during the presence of the sheet over the slot, and as cam-stop 15 cannot pass out of the way of projection 14 until the feeler passes through said slot, member 6 is stopped until the bottom edge of the sheet clears slot 4. The moment the sheet clears the slot, however, paper-feeler 28, no longer detained by the sheet, passes through the slot, and member 6, no longer detained by stop 15, takes up its movement with the platen. As member 6 begins its movement always when the bottom edge of the sheet is a fixed distance from the printing point, and maintains always a progress thereafter coöordinated with that of the sheet, bringing always the same point on member 6 opposite pointer 34 (attached to plate 2), when the end of the sheet attains 100 any given distance from the printing point, by making said member an index-carrier and supplying it with suitable indices, the distance from the printing point to the end of the sheet, or to a point a known distance therefrom, can be indicated from the time the paper-feeler is released until the sheet leaves the machine. As the carrier 6 begins its sheet-synchronized movement at a point intermediate in the printing of the sheet and at a point moreover the distance of which from the end of the sheet is not obvious nor readily calculable, the numeral beginning 110 such a series will be conveniently established in the first instance by experiment. It is to 120 130 140 150

be noted that the indicating surface upon the carrier 6 is divided into two segments, only one of which, that shown in the drawings as dark colored, is visible to the operator during the detention of the carrier, the other, that having the indices thereon and preferably colored white, lying concealed behind the shield-pointer 34 in this position of the carrier. When the carrier begins its indicating functions the dark segment disappears and the white segment bearing the indices takes its place, the striking change in color serving as a visual signal to the operator that he is nearing the end of his sheet.

Additional indicating means whereby I ring a bell after the completion of a predetermined amount of matter on the page, and after that block the machine so that no further printing can be done upon the sheet, are described as follows: Upon carriage frame 12 is attached frame extension 22 (Fig. 2), bearing a fixed pin 86 for the support of a bell 27. Carriage frame 12 also bears an inwardly projecting pin 37 and a corresponding pin opposite thereto on the inner side of the other end of the carriage frame, as will be understood. Upon this pin 37 is journaled a bushing or sleeve 38, bearing bail-piece 3 having an outwardly projecting turned end 54 thereon and having attached thereto a light spring wire or stem 72 supplied with a hammer-head 26. Spring 55, attached to the carriage frame by means of slotted post 56, is mounted so as to press downwardly against the turned-over end 54 of said bail-piece 3, sleeve 35 serving to limit the action of the spring. The other end of spring 55 is extended beyond post 56 so as to limit the movement of bail-end 54 in backward direction. Plate 2 carries an inwardly projecting pin 174, upon which is journaled a lever 1 having a hub 50. Said lever 1 projects into the path of pin 68, and one arm thereof bears an outwardly projecting pin 51. A connecting rod 53 connects said pin with an inwardly projecting pin 52 on the bail-piece. The arrangement of parts is such that the lowering and raising of plate frame 47 under the action of the usual shifting mechanism will not affect the operation of the mechanism just described, although part of it is stationed on the said platen frame 47 and part of it on carriage frame 12, which does not lower and rise.

When lever 1 is pressed against by pin 68 and turned by it upon its axis, bail-piece 3 is dipped downwardly, causing the bell hammer to strike bell 27. As the line-spacing mechanism usually employed in typewriting machines starts and stops the platen with considerable suddenness, this somewhat jerking action is avoided in the present instance as a simple means of operating the

bell. The operator is now warned that he can write but one more line upon the sheet. Upon its completion and the spacing forward of the sheet, lever 1 is turned still farther upon its axis by pin 68, with the result that bail-piece 3 is lowered still farther until it lies in the path of the types 73 on the typebars 78 so as to prevent the types from printing upon the sheet. The typebars 78, the axis 81, and the actuating connections therefor, are as in practice and need not be further described. Bail-piece 3 is preferably made of a light resilient material, faced with a substance non-harmful to the type, like leather. It is intended that the several above described indicating means are to be used with all the modification herein described.

Figs. 10 and 11 represent a modification in the arrangement and form of the paper controlled parts of my device. In this arrangement frame extension 45 attached to the frame 47 bears inwardly projecting pin 20^a. A sleeve 21¹ is journaled upon this pin, mounted upon which are the weight 66³ fixedly, paper-feeler 28¹ fixedly, and collar 105 fixedly, and the super-sleeve 104 loosely, the said super-sleeve bearing in its turn the fixedly attached cam-stop 15^a supplied with a cam surface 30^a. Cam-stop 15^a is also supplied with a lug to coöperate with a projection 62^a on weight 66³, so that when pressed in one direction it will act rotatively upon sleeve 21¹, but not when pressed in the other. The purpose of the provision is to permit of the free backing-up of the projection 14 past stop 15^a. Weight 66³ serves the purpose of restoring the stop 15^a and paper-feeler 28¹ into initial position. Paper-feeler 28¹ consists of an upper part bearing pin 23 and a lower part mortised therein and journaled upon said pin, lug 65 and mortise-bevel 24 coöoperating to limit the movement of said parts on one direction, to facilitate backing-up of the sheet. Finger-stop 42 (Fig. 11) attached against a shoulder of pin 20^a by the retaining nut 20^a on said pin is provided to engage upon said paper-feeler, to prevent displacement thereof. By means of the bolt 19 an auxiliary paper-support 8² is clamped upon brace-rod 18, said support coöoperating with the edge of paper-table 8 to form a slot 4^a, into which the paper-feeler has its path. Shield-pointer 34^a is attached directly to frame 47. In other respects the structure of this embodiment is like that already described, and its operation is essentially the same.

Figs. 12 and 13 represent another modification in which cam-stop 15 and arm 32 of Fig. 3 are combined in the cam-arm 15^b, bearing paper-feeler 28. Projection 14 acting upon this cam-arm along cam surface 30^b actuates paper-feeler 28 into slot 4^b in paper-support 8^a, attached by bolt 19 upon 130

rod 18. Instead of using spring 66 of Fig. 1 to return the paper-feeler into initial position I use a tail-cam 29, which when engaged by projection 14 lifts cam-arm 15^b out of slot 4 toward the platen until the parts affected are well past the center of gravity, after which they will fall by their own weight into initial position. In other respects the structure and operation of this form of the device is essentially like that of the first form described.

Figs. 14 and 15 represent still another modification in the form and disposition of the paper controlled parts. Platen frame 47 bears the inwardly projecting ears 49 supporting pin 20¹, which serves as an axle for the vertical lever-stop 15² supplied with a cam surface 30². That is to say, the axis of lever-stop 15² is perpendicular to a radial line drawn through axis of the member 6. I prefer to give it a vertical position, or one substantially vertical. The said vertical lever-stop 15² has attached to it a paper-feeler 28^a, which has a path through slot 4^c in paper-table 8. A spring 66¹ (Fig. 15) is used to return the paper-feeler out of the slot and into initial position. I prefer to slope the paper-feeler diagonally upward for the purpose of more smoothly guiding the backing-up bottom edge of the sheet out under the paper-contacting portion of the feeler. This, however, is not essential. It is to be noted that, while desirable, the cam contour 30 on stop 15² is not essential to the operation of this form of the device, nor to that of the forms shown in Figs. 1 and 10.

Fig. 16 represents still another modification, showing how the cam-stop and its cooperating rider may be interchanged, cam 30¹ here revolving in unison with member 6['] and acting upon an inwardly projecting pin 14¹ on arm 15³, journaled on pin 20^c inwardly extending from platen-frame 47, not shown in this figure. Said arm bears the inwardly projecting paper-feeler 28, having an action into slot 4^c in paper-table 8. A spring 66^c, held at one end by a pin 82 on platen frame 47 and at the other by pin 83 on arm 15³, serves to return paper-feeler 28 out of slot 4 and into first position against the platen. A key pin 60 is used in this modification to insure unison movement of spring 7^a with member 6[']. Instead of placing pin 68 in one of the seats 67 on disk 25 as in Figs. 4 and 9, I place it in one of the threaded seats 67^a on cam 30¹. The construction in other respects is essentially as has been described in connection with the early figures. The operation of this modification is as follows: Cam 30¹ through projection 14¹ actuates paper-feeler 28 against the sheet, and through the paper-feeler is then stopped by the sheet, the attached member 6['] being thus detained in initial position. When the sheet passes on from under

the paper-feeler, member 6['] is released as before, and through the said member the several indicating means are eventually called into operation.

Figs. 17, 18 and 19 represent another modification in the form of my cam-actuator. In this modification arm 15³ bearing paper-feeler 28 is journaled as before on inwardly-projecting pin 20^c on platen-frame 47 (not shown in these figures). Paper-feeler 28 has an action into slot 4^c in paper-table 8. Spring 66² bearing against pin 82 on platen frame 47 and against pin 83 on lever 15³ tends to actuate paper-feeler 28 against sheet 45, instead of away from it, the paper-feeler being returned to initial position against the pressure of spring 66² by the action of cam 30² upon inwardly projecting pin 14². The said cam 30² may be given unison movement with member 6² through spring 7^a, the spring and cam being connected conveniently by means of rivets 61 and a key-pin 60 insuring unison rotation of the spring with member 6². In one of the threaded seats 67^a on said cam is screwed the outwardly projecting pin 68. Lever 15³ bears a stop 15⁴, which at times has a position in the path of projection 14 on member 6². Spring 7^a presses said member into frictional connection with the platen by bearing upon an inner shoulder thereof under the pressure of thrust-collar 33. In other respects the structure is as has been described in connection with the early figures. The action of the modification is as follows: Frictionally connected member 6² moving with the platen brings the swell or bosom of cam 30² under pin 14², thus raising paper-feeler 28 into the position shown in Fig. 17. The sheet is then inserted. As the platen is rotated, the slope of the cam is brought under pin 14², and paper-feeler 28, under the actuation of spring 66² upon arm 15³, is lowered against the sheet and detained by it. In this position of parts stop 15⁴ on said arm lies in the path of projection 14. Further rotation of the platen brings projection 14 against stop 15⁴, and member 6², no longer able to rotate with the platen, is held detained until the end of the sheet passes from over slot 4^c and releases paper-feeler 28. It will be seen that when the end of the sheet clears the said slot, paper-feeler 28 will be pressed into the slot by the action of spring 66², and that this movement will withdraw stop 15⁴ from the path of projection 14, and that member 6² will thereupon take up movement with the platen. The several indicating means will now be called into operation through said member, as before. It is intended that the various parts shall move in such planes as not to interfere one with the other, pin 68 moving in a plane that is interior with respect to that of stop 15⁴. The action of spring 66² is in-

tended to be very light, in order that cam 30² may perform its work with little resistance.

The devices shown in the drawings and 5 described herein are part of a series of closely related inventions or improvements which are presented in a number of co-pending applications for Letters Patent filed by me. The said devices have a number of general 10 objects in common with those forming the subject matter of different applications in the said series, and to a certain extent embody and utilize various principles and features which are common to devices shown 15 and described in one or another of the said applications. Some of the said common principles and features are claimed broadly in Letters Patent No. 1,053,919, aforesaid, and in Letters Patent dated February 18, 20 1913, No. 1,053,920 granted upon my application filed March 30, 1912; No. 1,053,921, granted upon my application filed June 15, 1908, Serial No. 438,577; No. 1,053,922, granted upon my application filed December 25 1909, Serial No. 533,309; No. 1,053,923, granted upon my application filed December 13, 1909, Serial No. 532,928; No. 1,053,925, granted upon my application filed April 25, 1910, Serial No. 557,330; No. 1,053,928, 30 granted upon my application filed April 9, 1912, Serial No. 689,560; No. 1,053,929, granted upon my application filed May 27, 1912, Serial No. 699,958; and No. 1,053,926, granted upon my application filed April 4, 35 1912; Serial No. 688,358; and in my application filed December 5, 1912, Serial No. 735,108. The branch of the general invention that is covered hereby is distinguished by the following claims.

40 Having thus clearly explained my invention, I claim as new and desire to secure by Letters Patent—

1. In a typewriting machine, in combination, a platen, a detainable member actuated 45 from the platen, indicating means called into operation through said member, a paper-feeler, and a cam-stop connected to detain said member in starting position under the control of said paper-feeler.

50 2. In a typewriting machine, in combination, a platen, a detainable member actuated from the platen, indicating means called into operation through said member, a paper-feeler, and a cam and co-operating cam-follower, one thereof connected to move in 55 unison with said member and one thereof serving as a detent upon the other and one thereof controlled by said paper-feeler.

3. In a typewriting machine, in combination, a platen, an operative member having 60 a projection in connection therewith, indicating means called into operation through said member, means for giving said member movement coördinated with that of the platen but permitting detention thereof in-

dependently of the platen, a cam-stop in the path of said projection, and a paper-feeler in control of said cam-stop.

4. In a typewriting machine, in combination, a platen, a detainable member actuated 70 from the platen and having a projection in connection therewith, indicating means called into operation through said member, a cam-lever in the path of said projection, and a paper-feeler connected to control the 75 action of said cam-lever and itself actuated into the paper-path by said cam-lever.

5. In a typewriting machine, in combination, a platen, a paper-feeler, a spring for 80 retracting said paper-feeler away from sheet-controlled position to facilitate entering the sheet, an operative member actuated from the platen under the control of said paper-feeler, and indicating means called into operation through said member. 85

6. In a typewriting machine, in combination, a platen, a paper-feeler, actuating means for said paper-feeler including a spring and a cam, one of which is adapted to retract the paper-feeler from the paper-path and one of which actuates the paper-feeler into the paper-path, an operative member actuated from the platen under the control of said paper-feeler, and indicating means called into operation through said member. 95

7. In a typewriting machine, in combination, a platen, a slotted paper-backing, a reciprocating paper-feeler having a transversely-extending acting portion which rests 100 against the sheet at the slot and which when in sheet-held position is substantially parallel with the paper-backing, an operative member actuated from the platen under the control of said paper-feeler, and indicating means called into operation through said member. 105

8. In a typewriting machine, in combination, a platen, a paper-backing supplied with an opening, a transversely-extending paper-feeler having an action into said opening and having a normal waiting position retracted from said opening, an operative member actuated from the platen under the control of said paper-feeler, and indicating means called into operation through said member. 110

9. In a typewriting machine, in combination, a platen, a paper-backing having a slot, a transversely-extending paper-feeler having 120 an action into said slot, a spring for retracting said paper-feeler from said slot to facilitate entering the sheet, an operative member actuated from the platen under the control of said paper-feeler, and indicating means called into operation through said member. 125

10. In a typewriting machine, in combination, a platen, a detainable member actuated from the platen, indicating means 130

- called into operation through said member, and controlling means for said member including a reciprocating paper-feeler extending transversely past the sheet-edge, said 5 paper-feeler having a normal waiting position retracted from the sheet, it being actuated toward the sheet by said member and acting to detain said member in the presence of the sheet.
- 10 11. In a typewriting machine, in combination, a platen, a detainable member actuated from the platen, indicating means called into operation through said member, a stop connected to detain said member in 15 starting position, and a paper-feeler extending transversely past the sheet-edge and actuated against the sheet by said stop.
12. In a typewriting machine, in combination, a platen, a detainable member actuated from the platen, indicating means called into operation through said member, controlling means for said member including a paper-feeler extending transversely past the sheet-edge and actuated toward the 20 paper-path by said member and acting to detain said member in the presence of the sheet, and retracting means for giving said paper-feeler a position away from the paper-path.
- 30 13. In a typewriting machine, in combination, a platen, a detainable member actuated from the platen, indicating means called into operation through said member, a paper-feeler, the working portion of which has substantially a broadside presentation to the sheet, and coöperating detent elements, one thereof connected with said 35 detainable member and one thereof connected with said paper-feeler.
- 40 14. In a typewriting machine, in combination, a platen, an operative member actuated from the platen but detainable independently thereof, indicating means called into operation through said member, a paper-feeler, and sheet-controlled controlling means for said detainable member, including coöperating detent elements one of which revolves with said 45 detainable member and the other of which is controlled by said paper-feeler and has an axis substantially parallel with that of said revolving 50 detent element and within the arc described thereby.
15. In a typewriting machine, in combination, a platen, a detainable member actuated from the platen and having a projection in connection therewith, indicating means called into operation through said member, a lever-stop in the path of said 55 projection movable about an axis which is 60 radially interior of said path, and a paper-feeler connected to control the action of said lever-stop.
16. In a typewriting machine, in combination, a platen, an index-carrier having a 65 projection and an internal shoulder and supplied with a flanged ring bearing against said shoulder, indices called into operation through said carrier, a spring pressing said carrier into frictional connection with the 70 platen through said flanged ring, and a sheet-controlled stop in the path of said projection.
17. In a typewriting machine, in combination, a platen, a detainable member, an 75 audible signaling means called into operation through said member, frictional means for actuating said member from the platen, including a centrally pressed laterally acting spring, and sheet-controlled means for 80 controlling the movement of said member.
18. In combination, typewriter mechanism including a platen, a detainable member, means called into operation through said member for rendering a part or parts 85 of said typewriter mechanism inoperative for use, frictional means for actuating said member from the platen, including a centrally pressed laterally acting spring, and sheet-controlled means for controlling the 90 movement of said member.
19. In a typewriting machine, in combination, a platen, an index-carrier having indices, a reciprocating transversely extending paper-feeler, and operating devices for giving 95 said carrier operation from the platen under the control of said paper-feeler.
20. In a typewriting machine, in combination, a platen, an index-carrier actuated from the platen but detainable independently thereof, and controlling means for 100 said carrier including a reciprocating transversely extending paper-feeler, said paper-feeler actuated toward the sheet by said carrier and acting to detain said carrier in 105 the presence of the sheet.
21. In a typewriting machine, in combination, a platen, an index-carrier actuated from the platen, a stop connected to detain said carrier in starting position, and a 110 transversely extending paper-feeler connected to control said stop.

In testimony whereof I affix my signature in presence of two witnesses.

WILLIAM J. NEIDIG.

Witnesses:

THEODORE HOWELER,
JULIA HOWELER.
